(57) **CLAIM**

I claim the ornamental design for a bowl comprised of a top bowl, middle insert, and bottom, as shown.

DESCRIPTION

This application claims priority from U.S. patent application Ser. No. 13/368,214, filed on Feb. 7, 2012, by Jeffrey Brown, entitled Pet Bowl, the contents of which are expressly incorporated herein by this reference as though set forth in its entirety.

FIG. 1 is an enlarged view of a front-perspective view of the bowl comprised of a top bowl, middle insert, and bottom; FIG. 2 is a front-perspective exploded view of the bowl comprised of a top bowl, middle insert, and bottom;

FIG. 3 is an enlarged cross-sectional view of the bowl comprised of a top bowl, middle insert, and bottom taken along line 3-3 of FIG. 1;

FIG. 4 is a side elevational exploded view of the bowl comprised of a top bowl, middle insert, and bottom;

FIG. 5 is a top elevational view of the top bowl of the bowl comprised of a top bowl, middle insert, and bottom shown separated from the middle insert and bottom;

FIG. 6 is a bottom elevational view of the top bowl of the bowl comprised of a top bowl, middle insert, and bottom shown separated from the middle insert and bottom;

FIG. 7 is a top elevational view of the middle insert of the bowl comprised of a top bowl, middle insert, and bottom shown separated from the top bowl and bottom;

FIG. 8 is a bottom elevational view of the middle insert of the bowl comprised of a top bowl, middle insert, and bottom shown separated from the top bowl and bottom;

FIG. 9 is a top elevational view of the bottom of the bowl comprised of a top bowl, middle insert, and bottom shown separated from the top bowl and middle insert; and,

FIG. 10 is a bottom elevational view of the bottom of the bowl comprised of a top bowl, middle insert, and bottom shown separated from the top bowl and middle insert.
